US0D1018507S

(12) **United States Design Patent** (10) **Patent No.:** **US D1,018,507 S**
(45) **Date of Patent:** **** Mar. 19, 2024**

(54) **EARPHONE WITH CASE**

(71) Applicant: **ShenZhen Houshuxia Technology Co., LTD**, Shenzhen (CN)

(72) Inventor: **Shuxiao Ou**, Shenzhen (CN)

(73) Assignee: **SHENZHEN HOUSHUXIA TECHNOLOGY CO., LTD.**, Shenzhen (CN)

(**) Term: **15 Years**

(21) Appl. No.: **29/875,375**

(22) Filed: **May 3, 2023**

(30) **Foreign Application Priority Data**

Apr. 18, 2023 (EM) 015018503-0001

(57) **CLAIM**

The ornamental design for earphone with case, as shown and described.

DESCRIPTION

FIG. 1 is a first perspective view of a case of an earphone with case showing my new design, shown separately to show aspects of the design that are not visible when combined;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view of an earphone of the earphone with case, shown separately to show aspects of the design that are not visible when combined;

FIG. 10 is a second perspective view thereof;

FIG. 11 is a front view thereof;

FIG. 12 is a back view thereof;

FIG. 13 is a left side view thereof;

FIG. 14 is a right side view thereof;

FIG. 15 is a top view thereof;

FIG. 16 is a bottom view thereof;

FIG. 17 is a perspective view of the earphone with case, shown in a state of use with the earphones in the case; and, FIG. 18 is a front view thereof.

The broken lines shown in the drawings depict portions of the bluetooth earphone earphone with case that form no part of the claimed design.

1 Claim, 18 Drawing Sheets
